John Kroder:

BY

ATTORNEYS

UNITED STATES PATENT OFFICE.

JOHN KRODER, OF NEW YORK, N. Y., ASSIGNOR TO THE J. KRODER & H. REUBEL COMPANY, OF SAME PLACE.

DESIGN FOR A CURTAIN-POLE RING.

SPECIFICATION forming part of Design No. 32,654, dated May 15, 1900.

Application filed April 16, 1900. Serial No. 13,142. Term of patent 7 years.

To all whom it may concern:

Be it known that I, JOHN KRODER, a citizen of the United States, and a resident of the city of New York, borough of Manhattan, in the county and State of New York, have invented and produced a new and original Design for a Curtain-Pole Ring, of which the following is a full, clear, and exact description.

Reference is to be had to the accompanying drawings, forming a part of this specification, in which similar characters of reference indicate corresponding parts in both the views.

Figure 1 is a face view of a curtain-pole ring, showing my design; and Fig. 2 is an edge view of the same.

The design in its entirety consists of a split ring A, appearing at its ends with encircling hubs B B' and eyes C C' depending

therefrom and located one alongside the other 20 and in register with each other, as is plainly indicated in the drawings.

The leading feature of the design consists of the depending eyes appearing at the ends of the split ring. 25

Having thus fully described my invention, I claim as new and desire to secure by Letters Patent—

The design for a curtain-pole ring, as herein shown and described. 30

In testimony whereof I have signed my name to this specification in the presence of two subscribing witnesses.

JOHN KRODER.

Witnesses:

THEO. G. HOSTER,
EVERARD BOLTON MARSHALL.
